UNITED STATES PATENT OFFICE

CHARLES T. KENNEDY AND CHRIS W. VANDERMARK, OF ST. PAUL, MINNESOTA

HUMIDIFIER

Application filed April 10, 1930. Serial No. 443,150.

Our invention relates to a moist air generator and circulating device for use particularly in buildings heated by hot water, steam, or vapor, or where a continuous flow 5 of hot water or steam is available.

The main object is to provide a simple and highly efficient air moistening device or humidifier providing ample moist air, easily regulated according to requirements, as hereinafter fully set forth, reference being had to the accompanying drawings, in which,—

Fig. 1 is an elevation of a hot water plant with our humidifying device in operative connection, also showing in cross section two 15 rooms heated by said furnace and certain air circulating ducts. The device may be similarly connected to any heating plant where flow of hot water or steam is available, a hot water plant having been shown for il- 20 lustriative purposes only.

Fig. 2 is an enlarged vertically sectional elevation of our air moistener device, the sectional plane being assumed to be near the front wall of the device through its vertical 25 water conductor tubes.

Fig. 3 is a transverse sectional view of our device taken on a horizontal plane through its upper part about as on line 3—3 in Fig. 2.

Referring to the drawings by reference numbers, we have illustrated our device in operative combination with a hot-water heating plant designated 5, set up on a basement floor 6. 7 and 8 are two rooms above said furnace 5 and separated by a wall 9. 10 is the hot 35 water outlet pipe from the furnace and shown connected to a radiator 11 in room 7. 12 are the usual return water pipes from the various radiators and connected to a single down pipe 13 normally leading directly as at 14 40 into the lower part of the furnace.

Our device comprises a vertical box-like structure with an upper header 15 and a like lower header 16 fitted centrally to receive respectively the upper pipe section 13 and the 45 lower pipe section 13B leading to the furnace and known as the return pipe. It will be understood that the down pipe in this instance comprises two sections, 13 and 13B, in vertical alinement and spaced apart to 50 mount our device between them.

The headers 15 and 16 form respectively the upper and lower ends of an air tight drum consisting of a jacket 17 preferably quadrangular in horizontal cross section and held rigidly between the headers by suitable means such as the bolts 18 connecting the corner parts of the headers. Within the drum our device resembles in some respects a vertical tube boiler comprising a series of parallel vertical water tubes 19 retained in upper and lower sheet metal tube plates 20 suitably secured as with screws 21 to the headers 15—16 within the jacket 17. Above the upper plate 20 the header 15 is shallow providing a space 22 normally filled with hot return water from pipe 13, said water circulating downwardly through the tubes 19 to pipe 13B and from latter back to the furnace 5 through pipe 14 (see Fig. 1).

23 designates the parallel, flat spaces between the tubes 19 and having free communication with the space 23A exteriorly of the tubes and within the jacket 17. Our device creates a moist air condition in the drum by means presently to be described, warm moistened air circulating out through a conductor 24 from the upper part of the drum to the room or rooms as 7 and 8 in which are provided moist air registers 25.

26 is a cold air return air pipe from said rooms and entering the drum as at 26A near its lower end and preferably on the side opposite from which outlet pipe 24 extends.

The circulation of hot water through our device has now been fully set forth, it being readily understood that the exterior surfaces of tubes 19 are made quite warm and present considerable warm area within the drum. The air therein would of course naturally circulate through conductor 24 upwardly. Our moistening means for this volume of air consists of a water pipe 27 fixed horizontally within the drum to one side of and transversely with relation to the flat tubes 19 (see Fig. 3). This pipe 27 has suitable connection, as pipe 28, with a source of water under pressure, and is located in the upper part of the drum. 27A are a number of outlets from the pipe 27, each controlled, if so desired, by a needle valve 27V. The outlets 27A are 100

located and controlled to cause a fine spray of water in the spaces 23 between the tubes 19 and onto the walls thereof, the contact of the water on said warm walls of the tubes 5 creating a vaporization which provides the needed moisture in the air circulating upwardly and out of the drum through the conductor 24. The quantity of moist air is of course easily regulated at 27V by hand, or 10 any suitable automatic control may be used. 29 is a drain pipe extending from the lower part of the drum (shown in Figs. 1 and 2). The sprays 27A must of course be regulated so that the temperature of the air in the upper 15 part of the drum must be higher than at the intake 26A so as to insure proper circulation.

As a modification, the tubes 19 may be covered by fabric sleeves 30, shown in section on two of the tubes only in Fig. 3. Each 20 sleeve should fit a tube snugly and extend throughout its entire length, the material being preferably a saturatable woven fabric. Obviously these sleeves are saturated by the sprays and the water in them gravitates toward the lower end of the device, gradually 25 evaporating. It is further obvious that these sleeves retard the movement of water, and create desirable moist air condition, and there will be little or no waste quantity of water 30 to be drained at 29.

Our device has now been fully disclosed together with its method of operation. We have illustrated a preferred form. No forced 35 circulation is used, the action being simple, effective and natural circulation employed. Modifications may be embodied in various details and proportions of parts, etc., without departing from the scope and spirit of the invention.

40 We claim:

1. In an air moistening device the combination with a vertical hot-water conductor of an upright drum in said conductor means, a series of parallel flat water conducting tubes 45 within said drum, said drum comprising also an outer jacket with an upper air outlet and a lower air intake, a conductor from said outlet for circulation of air from said drum and means for generating moist warm air within 50 said drum.

2. In an air moistening device the combination with a hot-water conductor of a drum in said conductor means, a series of flat, parallel water tubes within said drum, said drum 55 comprising also an outer jacket with an upper air outlet and a lower air intake, a conductor from said outlet for circulation of air from said drum and means for generating moist warm air within said drum, comprising a 60 water conductor pipe fixed in said drum in position communicative with the spaces between said flat tubes, water outlet means in said pipe for spraying the outer surface of said tubes.

65 3. An air moistening device comprising an

upright drum consisting of a jacket retained between two headers, a series of fixed upright, flat water ducts mounted within said drum, means for mounting said drum in the hot water pipe of a furnace to provide a flow 70 of hot water through said device and its ducts, a warm air outlet from said jacket and an air intake in said jacket at a lower elevation than the outlet, woven fabric cover means for said ducts, and water spraying means mounted in 75 said drum and adapted to spray water between and on the adjacent parts of said tubes.

In testimony whereof we affix our signatures.

CHARLES T. KENNEDY. 80
